UNITED STATES PATENT OFFICE.

SAMUEL P. LANGDON, OF PHILADELPHIA, PENNSYLVANIA.

CATAMENIAL BANDAGE.

SPECIFICATION forming part of Letters Patent No. 727,159, dated May 5, 1903.

Application filed November 1, 1902. Serial No. 129,720. (No model.)

To all whom it may concern:

Be it known that I, SAMUEL P. LANGDON, a citizen of the United States, residing at Philadelphia, in the State of Pennsylvania, have invented a new and useful Catamenial Bandage, of which the following is a specification.

This invention is an improved catamenial bandage or sanitary napkin, the object of the invention being to provide a device of this kind which shall be simple in construction and exceedingly efficient in operation, being particularly adapted for use while traveling or at a time when frequent changes of an ordinary napkin would be impossible.

The principal advantages of the device constructed in accordance with my invention are that it can be adjustable to suit various-sized persons and when adjusted will absolutely prevent soiling the underclothes, and, furthermore, the absorbent pad can be quickly and easily detached, cleansed, and again connected to the main or body portion of the bandage.

The invention consists, essentially, in providing a waterproof bandage or napkin adjustably connected to a supporting belt and provided with a readily-cleansible absorbent pad detachably connected to the said bandage or napkin.

The invention consists also in the manner of connecting the said pad and in the manner of adjusting the napkin or bandage.

The invention consists also in certain details of construction and novelties of combination, all of which will be fully described hereinafter and pointed out in the claims.

In the drawings forming a part of this specification, Figure 1 is a detail perspective view of a device embodying my invention. Fig. 2 is a top plan view of the napkin and pad thereon. Fig. 3 is a bottom plan view of the napkin, showing the manner of connecting the pad. Fig. 4 is a section on the line 4-4 of Fig. 2, and Fig. 5 shows a detail of construction.

In carrying out my invention I employ a belt A, having front and rear depending portions A' and A'', each being provided with a hook A³, arranged upon the outer side of each

depending portion. This belt may be made 50 of any desirable material and provided with any suitable means for fastening the same around the waist.

The bandage or napkin B may be of any suitable or desirable material and has a facing 55 or lining C of waterproof material stitched to the upper side thereof, thus rendering the napkin or bandage proof against moisture. The napkin or bandage tapers toward each end, and the tapering portions are provided 60 with a series of eyelets B', into which the hooks A³ fit, thereby connecting the napkin to the belt, and by having a series of eyelets the napkin can be adjusted to suit various-sized persons. 65

An absorbent pad D is arranged upon the waterproof face of the napkin B about the center of the same, said pad being preferably made of sponge, though other material may be employed. This pad is detachably connected to the napkin by lacing-cords E, which pass through the pad from the upper side near each end down through eyelets B², fixed in the napkin, the ends of said cord being held upon the under side of said napkin, as 75 most clearly shown in Fig. 3. This enables the wearer to remove the pad at any time quickly and easily, clean the same, and replace it. Thus one bandage of this description will be sufficient and at the same time 80 the sanitary conditions will be greatly improved. A bandage of this character will also accommodate itself to the position of the wearer and will be thoroughly comfortable in both a sitting and standing position. 85

Having thus fully described my invention, what I claim as new, and desire to secure by Letters Patent, is—

1. A device of the kind described comprising a belt, a waterproof napkin, eyelets in the 90 body of the napkin, an absorbent material placed in the napkin and adapted to cover the eyelets, cords adapted to pass through the eyelets and absorbent material and be tied on the exterior of the napkin, and means for 95 securing same to the belt.

2. A device of the kind described comprising a belt having depending side portions,

hooks secured thereon, a waterproof napkin having a plurality of eyelets adjacent each end adapted to engage the hooks, eyelets arranged in the body portion of the napkin, a 5 sponge placed in the napkin and adapted to cover said eyelets, and cords passed through the eyelets in the body of the napkin and

covered by the sponge, each cord being passed twice through the sponge and tied on the under side of the napkin.

SAMUEL P. LANGDON.
